UNITED STATES PATENT OFFICE.

NEIL MACNEALE, OF CINCINNATI, OHIO, ASSIGNOR TO THE CORCORAN-VICTOR COMPANY, OF CINCINNATI, OHIO, A CORPORATION OF OHIO.

DESIGN FOR A LAMP-DOOR.

58,676.

Specification for Design.

Patented Aug. 9, 1921.

Application filed March 15, 1920. Serial No. 366,113. Term of patent 7 years.

To all whom it may concern:

Be it known that I, NEIL MACNEALE, a citizen of the United States, and a resident of Cincinnati, in the county of Hamilton and State of Ohio, have invented a new, original, and ornamental Design for a Lamp-Door, of which the following is a specification, reference being had to the accompanying drawing, forming a part thereof.

In the drawing,

Figure 1 is a front elevation of my lamp door.

Fig. 2 is a side elevation of a lamp showing my lamp door thereon.

Fig. 3 is a section taken centrally of Fig. 1 to illustrate the conformation of the door.

In the drawing, the shading indicates a color variation between the parts 1, 2, and the parts 3, 3, preferably the parts 1, 2 being nickel and the parts 3, 3, black.

I claim:

The ornamental design for a lamp door, as shown.

NEIL MACNEALE.
